CANOPY FOR A GASOLINE DISPENSING STATION

Watrons A. Nielsen, Chicago, Ill., assignor to
Card, Inc., Chicago, Ill.

Filed Jan. 14, 1970, Ser. No. 20,918

Term of patent 14 years

Int. Cl. D25—03
U.S. Cl. D13—1

FIG. 1 is a front elevational view of a canopy for a gasoline dispensing station embodying my new design;

FIG. 2 is a side elevational view thereof; and

FIG. 3 is a top plan view thereof on a reduced scale.

I claim:

The ornamental design for a canopy for a gasoline dispensing station, as shown.
